ATTORNEY

UNITED STATES PATENT OFFICE

WESLEY C. MARTIN, OF DONNELSVILLE, OHIO

ENGINE-MOUNTING MEANS

Application filed August 12, 1927. Serial No. 212,572.

The object of this invention is to mount an engine on a motor car or the like in such manner that it may be swung from a vertical position outwardly over the frame of the vehicle, to permit of repairs, cleaning and adjustment, without the necessity of doing the work from the underside in accordance with the usual practice.

A further object is to effect this result by mounting the engine on supporting means carried indirectly by the side element of the car frame, and carried directly by the flanged portion of the oil pan of sufficiently substantial construction to enable it to sustain the weight required.

A further object is to provide means including a segmental rack bar to be carried by the base or bed plate of the engine and adapted for engagement by a pinion mounted on an element of the starting crank, the pinion and rack being normally in mesh but automatically thrown out of mesh when the crank is moved to operative position with reference to the crank shaft of the engine.

A further object is to provide particular means for connecting the base of the engine with the oil pan employed, a plurality of bolts being pivotally mounted and adapted to be swung outwardly when nuts are loosened, from engagement with the base or bed plate, the heads of the bolts being apertured and engaging a bar or bars by which the pivotal mounting is effected.

With the foregoing and other objects in view, the invention consists in the novel construction and arrangement of elements hereinafter described and claimed, and illustrated in the drawings, it being understood that modifications may be made within the scope of the claims without departing from the spirit of the invention.

In the drawings forming part of this application,

Figure 1 shows an engine in elevation and in its normal operative position.

Figure 2 is an elevation showing an engine thrown outwardly, for the purpose previously indicated.

Figure 3 is a detail view showing the manner of mounting the bolts.

Figure 4 is a detail view showing a pinion carried by the starting crank, and a portion of the rack with which the pinion meshes.

The main portion of the engine is shown conventionally, and is designated 10, a base portion or bed portion including an outwardly extending flange 11 provided with slots 12 for the accommodation of bolts by which the engine is secured in the position of Figure 1. A spark plug is designated 14, and a pan is shown in dotted line at 15.

An oil pan is designated 16 and includes an outwardly extending flange 17 adapted to rest on the side elements of the frame of the vehicle. The oil pan will be of sufficiently substantial construction to serve the purpose set forth in this case, it being observed that the engine is carried by brackets such as 18 mounted on the flange 17 and adapted for pivotal connection with extensions or brackets 19 on the base portion of the engine. The engine is further supported however, in the position of Figure 2, by the segmental element referred to below.

Bolts 20 include heads 21 each having a shoulder, 22 and having a central aperture permitting of the mounting of the bolts on rods such as 23, whereby the bolts are adapted to swing outwardly to the dotted line of Figure 3, when the nuts 24 are loosened, the bolts then moving thru the slots 12 and 12', and when in the dotted line position of Figure 3, the bolts are instantly accessible for use in again connecting the engine with the frame of the oil pan, after repairs or adjustments have been made. The rods 23 are mounted in brackets such as 25 suitably positioned on the outer portion of the oil pan and below the flange 17 thereof.

In Figure 4, a starting crank is designated 28 and includes or carries the socket portion 29 slotted at 30 and adapted to engage the pin 31, in the usual manner, when moved to operative position, for the purpose of turning over the spark plug.

The socket portion 29 carries a pinion 32, rigidly mounted and adapted to mesh with a rack 33 rigidly mounted with reference to the base of the engine, this rack being of segmental form and at its lower end, or at one

end having a stop 35 acting to limit the movement of the engine when swung outwardly. The usual spring for the starting crank is designated 28', and it will be observed that when the crank is disconnected, or in normal position, the pinion 32 is in mesh with segment 33, so that the engine may be tilted upon the loosening of the bolts 20.

This arrangement avoids the great inconvenience arising from the necessity of gaining access to the crank shaft bearings, from beneath the car, under ordinary conditions, and permits the workman to handle the operation under way more efficiently, and in less time.

Claims:

1. The combination with an engine structure and a rack element rigidly carried thereby, of supporting means, means pivotally mounting the engine with reference to the supporting means, said rack being movable in an arc-shaped path about the pivotal mounting and continuously supporting the engine from the base thereof during lifting movement, a starting crank for the engine, and a pinion rotated by the crank and meshing with the rack element.

2. The combination with an engine having a crank shaft, and a rack element rigidly carried by the engine structure, of an oil pan, means for pivotally mounting the engine on the pan, said rack being movable in an arc-shaped path about the pivotal mounting and continuously supporting the engine from the base thereof during lifting movement, a starting crank, and means operated by the crank when disconnected from the crank shaft for engaging the rack element, and tilting the engine laterally.

3. The combination with an engine having a flanged base, of engine supporting means, and bolts pivotally mounted on the supporting means and adapted to swing from a position in engagement with the flanged base to an outer inoperative position, said bolts including heads having shoulders adapted for engagement with the supporting means.

In testimony whereof I affix my signature.
WESLEY C. MARTIN.
